UNITED STATES PATENT OFFICE.

JEREMIAH M. SHAY, OF FALL RIVER, MASSACHUSETTS, ASSIGNOR OF ONE-HALF TO A. B. PITKIN MACHINERY COMPANY, OF PROVIDENCE, RHODE ISLAND, A CORPORATION OF RHODE ISLAND.

WEFT-REPLENISHING MECHANISM FOR LOOMS.

SPECIFICATION forming part of Letters Patent No. 696,657, dated April 1, 1902.

Application filed August 18, 1900. Serial No. 27,045. (No model.)

To all whom it may concern:

Be it known that I, JEREMIAH M. SHAY, a citizen of the United States, residing in Fall River, in the county of Bristol, in the State 5 of Massachusetts, have invented certain new and useful Improvements in Weft-Replenishing Mechanism for Looms; and I declare the following to be a specification thereof, reference being had to the accompanying drawings.

In the art of weaving as carried out with looms as now commonly constructed the objection has been experienced that when the weft breaks or the cop of the shuttle becomes 15 exhausted the loom is automatically stopped through well-known connections and the shuttle therein must be removed and a fresh shuttle supplied by the hand of the operator before the said loom can again be put into operation.

The object of the present invention is the provision of means capable of perfect automatic operation for the placing in proper position of a fresh shuttle when the weft breaks 25 or runs out, the said means being also operated to effect the discharge of the empty shuttle when the fresh one is being supplied to the shuttle-box.

My invention consists of a receptacle for 30 receiving the fresh shuttle and operating devices therefor in connection with the moving parts of the loom for automatically placing a fresh shuttle in the shuttle-box at the proper moment, and thus placing the fresh shuttle 35 contained by it into proper position to be struck by the picker-stick at its next throw.

It consists, further, in the peculiar construction and arrangement of the shuttle-box and operating mechanism by which the empty 40 shuttle is discharged.

It further consists of shears or cutters for automatically cutting the weft or thread projecting from the selvage of the cloth after the fresh shuttle has been thrown through the 45 shed.

The details of construction relating to the various operating devices and their arrangement also constitute a material part of this invention as enabling me to accomplish the desired result in a simple and practical manner.

Figure 1 is a central vertical sectional view of the loom, showing the position of the various parts when the shuttle is in the box at the left-hand side of the loom and the lay has come to the end of its rearward motion. Fig. 55 2 is a central vertical sectional view of a portion of the loom, showing the position of the various parts after the weft has been thrown through the shed of the warps and the shuttle has entered the shuttle-box and the lay 60 has come to the end of its forward motion. Fig. 3 is a vertical sectional view of a portion of the loom, showing the position of the various parts after the weft is broken or has been exhausted and the empty shuttle is about 65 to be discharged, the lay having traveled three-fourths of its rearward motion. Fig. 4 is the same as Fig. 3 with the addition of the shuttle-ejecting mechanism to remove the empty shuttle from the shuttle-box. Fig. 5 70 is a vertical sectional view opposite to Fig. 2. Fig. 6 is a vertical sectional view opposite to Fig. 3, showing the position of the various parts as the fresh shuttle is placed in the shuttle-box, the lay having reached the end 75 of its rearward motion. Fig. 7 is a front elevation of the upper portion of the left-hand end of the loom. Fig. 8 is a front elevation of the upper portion of the right-hand end of the loom. Fig. 9 is a top plan view of the left- 80 hand end of the loom. Fig. 10 is a top plan view of the right-hand end of the loom. Figs. 11, 12, and 13 show in side elevation the shears or cutters and means for operating the same. Figs. 14 and 15 show in side elevation a modified form of the shuttle-ejecting mechanism. Fig. 16 is a transverse vertical section of the shuttle-receiving pan and adjacent shuttle-box in position when the shuttle has been discharged into the pan. Fig. 17 is a side elevation 85 of the switch-block. Fig. 18 is a sectional view of the same as seen on line $z-z$ of Fig. 17. Fig. 19 is a top plan of the shuttle in the reservoir and the pusher or shuttle-transferrer in its normal position. Fig. 20 is a sectional view 90 of the same on line $z-z$ of Fig. 19. Fig. 21 is a top plan view of the same parts as are illustrated in Fig. 19, showing the preliminary angular position of the shuttle in entering the shuttle-box. Fig. 22 is a front elevation of 95

the same. Fig. 23 is a top plan of the bunter and mechanism for operating the cutting devices as seen when the lay is at the limit of its backward movement. Fig. 24 is a view 5 of the same as seen partly in elevation and partly in section on line $y-y$ of Fig. 23. Fig. 25 is a top plan of the same parts as seen when the lay is at the end of its forward movement and the bunter is in contact with the lever- 10 arm of the mechanism operating the cutting devices. Figs. 26 and 27 are views of said mechanism as seen partly in elevation and partly in section on line $w-w$ of Fig. 25. Figs. 28 and 29 are detail views. Figs. 23 to 29, inclusive, are drawn on an enlarged scale. Figs. 30, 31, and 32 are detail views, in an enlarged scale, of certain portions of said invention. In Figs. 2, 3, 4, and 15 the reeds shown in 15 Figs. 1 and 14 are omitted to simplify said drawings.

In the drawings, 1 represents the frame of the loom, 2 is the arch, 3 the harnesses, 4 the lay, 5 the picker-stick, 6 the breast-beam, 7 the dagger, 8 the sand-roller, 9 the cloth- 25 roller, 10 the gear for the cloth-roller, and 11 the feed ratchet-gear, all of the usual construction and operating in the well-known manner.

The shaft 12 has the cams 13 14 thereon, the 30 former of which operates the picking-arm 15 and the latter of which operates the bent lever 16, as usual. The shaft 12 is operated in the direction of the arrow, Fig. 1, through a suitable gear fastened to the opposite end of 35 the shaft and meshing with the gear 17, which is fastened to the crank-shaft 18, Fig. 8.

A filling-detector, operative to show the presence or absence of the filling or weft thread in the warp-shed, consists of the weft-fork 19, which is pivotally mounted at 20 to the sliding plate 21, the latter being movable in suitable bearings upon the casting 22. Said casting is fastened by bolts to the breast-beam 6. The end of the weft-fork nearest the breast-beam is hooked, as seen in Figs. 1 and 2, and 40 said hooked end is elevated at each throw of the shuttle whenever its opposite end is depressed by the weft-thread, which has been carried across. At each revolution of the 45 shaft 12 the cam 14 thereon imparts an oscillating movement to the bent lever 16, mounted pivotally at 23 on a bracket of the frame 1; but the elevation of the hooked end of the weft-fork, as above explained, lifts said end 50 out of the path of motion of the upper bent end of the lever 16. When the loom is in operation, the weft or filling thread is properly laid between the warps within the shed formed by the movements of the harnesses 3 as the 55 shuttle is struck by the pickers 24 of the picker-sticks 5 and thrown from side to side of the lay. The weft as the lay 4 comes forward lies in the path of the fingers of the weft-fork, thus depressing that end of the weft-fork and raising its hooked end, as already 60 stated. These parts and the operation of these

parts are all old and well known, being used in the ordinary looms for plain weaving.

My shuttle-changing mechanism, which constitutes the principal feature of my invention, is set in operation by the engagement of the bent upper end of the lever 16 with the hooked end of the weft-fork 19. If the weft-thread breaks or the weft in the shuttle becomes exhausted, the shuttle enters the shuttle-box, as usual; but when the lay 4 comes forward there is nothing to depress the rear end of the weft-fork, as before, and when the lay 4 has nearly reached the limit of its forward motion the front hooked end of the weft-fork is caught and engaged by the upper end of the bent lever 16 (see Fig. 1) and draws forward said weft-fork and the sliding plate 21, to which it is pivoted. This forward movement of the sliding plate causes the front 75 end thereof to bear forcibly against and push the upper bent end of the lever 25, which lever is fastened to the rock-shaft 26, Figs. 1 and 2, thus partially rotating the said shaft 26. Said rock-shaft is mounted in suitable 80 bearings 27 28, Figs. 9 and 10, which are fastened to the breast-beam 6. On the opposite end of the rock-shaft 26 and fastened thereon by the screw 29 is the lever 30. At the bottom of the lever 30 a link bar or rod 31 is 85 loosely pivoted, as seen at 32, and at the opposite end of said link bar or rod 31 it is pivoted, as shown at 33, to the end of a lever-arm 34, which is fastened to the axis 35 of a switch 36, which switch and lever-arm 34 move 90 together. The switch 36 is mounted in suitable 95 bearings in the block or casting 37, the latter being secured to the side of the loom. The block or piece 37 has on its outer surface a groove cut therein, (represented by the dotted 100 lines 38 and 39,) and it is also slotted to form a guide or way, as shown by the dotted line 40. (See Figs. 5 and 6.) The face view of 105 said switch-block and a vertical section thereof are shown in Figs. 17 and 18, in which 38', 39', and 40' represent, respectively, the upper 110 and lower edges of said groove and the bottom of said slot. When the switch 36 is in the position shown in Fig. 5, its under side is 115 continuous with the upper edge of the groove in said block 37; but when said switch is in the position shown in Fig. 6 its end is in contact with the lower edge 38 of said groove. The rocking of the shaft 26 caused by the 120 movement of the lever 25, resulting from the engagement of the upper end of the lever 16 with the hooked end of the weft-fork 19 and the consequent sliding of the plate 21, as already described, moves the switch 36 from its 125 inoperative normal position (shown in Fig. 5) to its operative position. (Shown in Fig. 6.) Upon a rock-shaft 41, which extends along the lay 4 from side to side and which is mounted in suitable bearings 42 and 43, Figs. 7 and 8, is fastened a lever-arm 44, whose lower 130 end is provided with a friction-roller 45 and whose opposite end is formed into a sector-

shaped gear 46. The lever-arm 44 is usually in the position illustrated in Fig. 5, and as the lay moves back and forth the friction-roller 45 of said lever-arm 44, projecting into the groove 38 39, is confined thereto in its movement from end to end thereof; but when the switch 36 has been moved by the rock-shaft 26 and its connections to the position shown in Fig. 6 said roller 45 as the lay moves 10 backward runs up along the upper surface of the switch 36 to and along the bottom 40 of the slot of the block or piece 37. The result of this movement is that the lever-arm 44 changes its angular direction from that 15 shown in Fig. 5 to that shown in Fig. 6, thus partially moving the sector-shaped gear 46, which is integral with or fastened to said lever-arm 44.

The shuttle-boxes used in my improved 20 loom constitute the principal and most important part of my invention. At each end of the lay is a shuttle-box, designated in the drawings as 47 and constructed as follows: It has a front and back side and one closed 25 end, but has no bottom. When it is in its usual horizontal position, as in Fig. 1, it rests on the top surface or race-plate 48 of the lay; but when it is turned up into its perpendicular position, as in Figs. 3 and 32, its bottom 30 is open. Each of said shuttle-boxes 47 has at its ends earpieces 49 and 50, by which it is loosely and rotatably mounted on the rod 51, the latter being mounted loosely in brackets 52, bolted or fastened to the front of the 35 lay 4. The earpiece 49 of each shuttle-box 47 is provided with a sector-shaped gear 53.

On the rock-shaft 41, at the left-hand end thereof, is fastened a sector-shaped gear 54. The gear 46 of the lever-arm 44 meshes with 40 the gear 53 of the right-hand shuttle-box 47, and the gear 54 on the opposite end of the rock-shaft 41 meshes with the gear 53 of the left-hand shuttle-box 47. When by the rocking of the shaft 26, caused by the engagement and movement together of the weft-fork 19 and the upper end of the bent lever 16 and the connections of said rock-shaft 26, the switch 36 is moved into the position shown in Fig. 6, the friction-roller 45 of the lever-arm 44 runs up said switch into the upper slot of the block 37, thus changing the angular direction of the lever-arm 44, and thereby moving the gear 46 of said lever-arm, and a similar oscillatory movement is imparted to 55 the gear 54, because both the gears 46 and 54 are fastened to the shaft 41, which is thus rocked. These gears 46 and 54 so moving impart motion to the gears 53 of the shuttle-boxes 47. Thus said shuttle-boxes begin to 60 turn up when the lay has performed nearly one-fourth of its backward movement, and by the time when the lay has completed its backward movement the shuttle-boxes 47 have come into the position shown in Fig. 3. 65 Behind the right-hand shuttle-box is a stationary reservoir or case 55 to hold the spare shuttles, which are to be supplied one by one

to the shuttle-boxes as the operating-shuttle becomes empty or its weft-thread is broken. This reservoir or case 55 is wholly independent of the lay, being supported by braces 56 from the arch 2. It has an open flaring top and at its front and rear at the bottom an open space exceeding somewhat in width the width of the shuttle. In this reservoir 70 spare shuttles are packed, each supplied with a suitable quantity of weft-thread, and there is a vertical opening in the front of the case to enable the operator to see the number of spare shuttles in the reservoir. On the front 75 of this case or reservoir 55 a lever or rocker arm 57 is pivoted at 58, the shorter arm of this lever being a weight or counterpoise. The upper end of the lever 57 is bent, as shown at 59 in Fig. 5, and the loose end of each of the 80 weft-threads from the spare shuttles in the reservoir is carried to and wound around said bent end of the lever, as seen in Figs. 5 and 10. On the sides of the case 55, inside the same and at the bottom, are placed two openings 85 or yielding detents, as seen at 55' in Fig. 19. On the rock-shaft 41 is also fastened a lever-arm 60, Figs. 5 and 6, and at its end is pivotally connected a link-bar 61, slotted at 90 its end. On the binder-shaft 62 and fastened thereto is the lever-arm 63, from which projects the bent or hooked arm 64, whose end is received in the slot of the lever 63. A coiled binder-spring 65, suitably fastened at its bottom to the frame of the loom, has its upper 95 end caught on the hook of the lever 64. An arm 66 is also fastened on the binder-shaft 62 and usually extends in the direction shown in Fig. 5; but when the arm 66 is depressed by the rocking of the shaft 41 it is brought 100 into contact with the forward lower end of the lever 67, (which is pivotally mounted at 68 to a bracket on the loom-frame.) This occurs when the lay has traveled about three-fourths of its backward motion, and its further rearward movement causes the arm 66 to push and move said lever 67. The lever 105 67 at its top is pivotally connected at 69 with a link-bar 70, to which is fastened at 71 a pusher or shuttle-transferrer 72. The forward end of the link-bar 70 is supported by a bracket 73, as shown. The reservoir 55 has a rearward extension 74, opening into the lower portion thereof and receiving the pusher 72. The rearward movement of the lay 4, in the swords 110 75 of which the binder-shaft 62 is mounted, causes the end of the lever-arm 66 to push and move the lower end of the lever 67, which movement of the lever 67 by the link-bar 70 moves the pusher 72 from the position shown 115 in Fig. 5 to the position shown in Fig. 6. The result of this movement of the pusher 72 is that the lowest shuttle in the reservoir 55 (shown in Fig. 5) is moved out of the reservoir into the shuttle-box, as illustrated in 120 Fig. 6. The springs 55' in said reservoir (see Figs. 19, 20) serve to hold whichever shuttle is at the bottom of said reservoir against displacements which might result from the jar-

ring or vibrations of the loom when operating; but they do not hold said shuttle sufficiently to interfere with the action of the pusher 72 in removing said shuttle from the reservoir 5 into the shuttle-box. On the withdrawal of the pusher 72 by force of the spring 76 the lowest shuttle at that time in the reservoir falls by its weight to the bottom of the reservoir, to be pushed into the shuttle-box whenever the pusher is operated again, as above described, said spring-detents 55 in the meanwhile pressing on the two pointed ends of said shuttle to hold it in place awaiting said operation, as seen in Fig. 19. The binder-spring 15 65, which by this movement has been stretched, as seen in Fig. 6, is by the forward movement of the lay 4 relieved from tension, and the arm 6 resumes its former position, as in Fig. 5.

The mechanism for removing the empty 20 shuttle from the left-hand shuttle-box is as follows: The left-hand end of the binder-shaft 62 is bent, as seen at 77 in Figs. 1 and 14, and upon this bent end a binder-finger 78 is fastened. The usual function of said binder-finger 78 is to press against the swell or binder 25 79 of the shuttle-box 47, as illustrated in Fig. 1; but when the binder-shaft 62 has been rocked, as already explained, by the lever 60 of the rock-shaft 41 and the intermediate connections 61, 62, 63, and 64 said binder-finger comes into the position shown in Figs. 4 and 6. Upon the arch 2, Fig. 4, is fastened the receiving-pan 80. This pan is also supported by the brace 81, extending from the frame of 30 the loom. A bracket 82, fastened upon the side of the pan 80, serves to support the vertical rock-shaft 83. A bent lever 84 is secured to the vertical rock-shaft 83 at the bottom thereof and is provided at one end with a head and 35 at the other it is connected with a spring 85. An arm 86 is fastened to the top of said vertical rock-shaft, Figs. 4 and 9. The end of said arm 86 is slotted, as seen at 87. A rod 88 has a head, through which a screw 89 passes 40 into the slot 87 of the arm 86. Said rod 88 is supported by and longitudinally movable in the bearings 90 and 91, fastened to the guide-plate 92, which partially covers the pan 80. A push-plate or shuttle-transferrer 93 is secured upon the end of the sliding rod 88 and 45 has a bent extension 94, as shown in Fig. 9, which is slotted at its end, as shown in Fig. 4. The pan 80 is so placed as to be above the top of the left-hand shuttle-box when the latter is in its normal position and the lay has 50 reached the limit of its rearward movement. At that time the bottom of the pan 80 extends somewhat over the top of the shuttle-box and partially covers the same. The front 55 top edge of the shuttle-box slightly projects inwardly. Fastened to the back of the shuttle-box is the usual spring, as in Fig. 22, which continually presses the swell or binder 79. Thus as the shuttle-box is turned from 60 its horizontal to its perpendicular position, as already specified, the shuttle therein is held in said shuttle-box by the pressure of

the binder 79 on said shuttle. A lever 95 is pivotally mounted on the back of the shuttle-box, as seen in Fig. 4, and has its short 70 end behind or under the free end of the binder 79 and its long end extending at an angle. An arm 96 is fastened to the side of the pan 80 and projects angularly upward. A door or shutter 97 is hinged in suitable bearings 75 on the inside of the shuttle-box and above the path of the travel of the shuttle therein. This door or shutter is held in a horizontal position even with the top of the shuttle-box by the spring 98, which is fastened to the top 80 of the gear by the rivet 99 at one end, the other end sliding loosely in the strap 100 on the door or shutter, as shown in Fig. 9. A spring 101 is fastened to the front of the shuttle-box and has a projection 102, which passes 85 under the front of the shuttle-box and below the raceway 4^a of the lay when the shuttle-box is in its normal position. A mortise 4^b is made in the raceway to receive said projection 102. These parts are shown in detail 90 in the enlarged views, Figs. 30, 31, and 32. This mechanism at the left-hand end of the loom is operated as follows: When the shuttle-box is turned up into the perpendicular position and the lay 4 has reached the position shown in Fig. 4, the rearwardly-bent end 77 of the binder-shaft 62 is depressed, as before described, thus moving the binder-finger 78 backward. Then as the lay continues its backward movement the top end of the binder-finger 78 comes in contact with the front end or head of the lever 84 and forces back said lever against the tension of the spring 85. This movement of the lever 84 partially rotates the vertical rock-shaft 83, and this turning of the rock-shaft 83 swings the slotted arm 86, and so draws the sliding rod 88. As the lay comes near the end of its backward motion the sliding rod 88, drawn as just described, brings the push-plate 93 in contact 100 with the empty shuttle and forces it into the receiving-pan 80. As the shuttle-box is raised to the position shown in Fig. 4 the end of the long arm of the lever 95 comes in contact with the arm 96 of the pan 80, thus depressing 105 said end of the lever 95 and raising its short end. This short end of the lever in rising lifts the free end of the binder 79 and relieves the shuttle from the pressure thereof. The shuttle is then free to be thrown 110 into the pan 80 by the action of the sliding rod 88 and its push-plate 93, as above explained.

Sometimes during the operation of the loom the speed of the main shaft, which operates the loom, will vary. If the speed has 115 considerably increased, the throw of the picker-stick will be more forcible, and consequently the shuttle will enter the shuttle-box at a greater velocity, and striking the 120 picker-head in the box, which it so enters, is liable to rebound one or two inches. At such time if the shuttle is about to be ejected from the shuttle-box into the receiving-pan it will 125 130

not be in a position to properly enter the pan; but as the sliding rod 88 is drawn the projecting bent end 94 of the push-plate 93 comes in contact with the door or shutter 97, 5 thus forcing back said door or shutter against the pressure of its spring 98, and as the door 97 shuts it crowds the shuttle toward the picker-head from which it rebounded and into such position that it properly enters the 10 receiving-pan 80 when pushed out, as described, by the push-plate 93. The continuous striking of the point of the shuttle against the picker 24 makes a hole in the picker, and when the tension of the binder 79 is perfect 15 the shuttle will not rebound from the picker, and so if the empty shuttle is about to be discharged as the shuttle-box turns up from the lay the point of said shuttle is held by the hole in the picker, thus preventing that end 20 of the shuttle from rising with the shuttle-box against the pressure of the binder 79; but the projection 102 of the spring 101 (see Fig. 31) holds said end of the shuttle in the 25 shuttle-box as the shuttle-box rises from the lay and the angle of the hole in the picker forces the shuttle forward in the shuttle-box, thus releasing the point of the shuttle from the picker. During this operation the spring 101 is held back against the front of the 30 shuttle-box by the cam-arm 103, which is fastened to the lay by the screws 104; but as the shuttle-box rises to the position shown in Fig. 4 the spring 101 is above the top of the cam-arm 103, thus allowing the spring to move 35 back to its normal position, so that the projection 102 is below the path of the empty shuttle, which is about to be discharged, Figs. 4, 9, and 32. When the lay 4 has come to the end of its backward motion, Fig. 6, the 40 empty shuttle has been discharged into the receiving-pan 80 and the lowest fresh shuttle in the reservoir 55 has been pushed in the right-hand shuttle-box and is held therein by the pressure of the spring of the binder 79. 45 Then as the lay 4 moves forward the roller 45 of the lever-arm 44 runs down the slot 40 of the block 37, thus bringing down said lever-arm 44 and moving forward the sector-shaped gear 46, which meshes with the sector-shaped 50 gear 53, mounted on the shaft 51 and fastened to the shuttle-box 47, Figs. 5 and 6. Thus as the lay 4 reaches the end of its forward beat the shuttle-box rests upon the lay with a fresh shuttle therein contained ready and in position 55 to be struck by the next throw of the picker and picker-stick. As the lay 4 starts on its forward motion just described the pressure of the upper end of the binder-finger 78 is removed from the front end of the lever 84 and 60 the rear end of said lever is drawn back by the spring 85, thus partially rotating the vertical rock-shaft 83, and thereby swinging forward the slotted arm 86. This moves forward the sliding rod 88 and withdraws the push-plate 93 65 from the interior of the left-hand shuttle-box, which is placed in position on the raceway as the lay 4 finishes its forward motion. Now as

the lay so comes to the end of its forward motion the rock-shaft 41, through connections with the roller 45, (which runs down the slot 40 70 of the block 37, and thus moves down the lower end of the lever-arm 44,) is partially rotated to its former and normal position. This return rotation of the shaft 41 moves back the lever-arm 60, which by its connected lever 61 75 releases the lever 64. The spring 65 is then free to pull down the lever 64, which partially turns the binder-shaft 62, and thus raising the projecting bent end of said shaft 80 crowds the upper end of the binder-finger 78 85 against the binder, Figs. 5 and 6. When the shuttles have been thus changed and the lay comes to the end of its forward motion, the bent lever 16 assumes a position almost similar to that shown in Fig. 1, and so releases 85 its upper end from the hooked end of the weft-fork 19, which through connections with the sliding plate 21, lever 25, and rock-shaft 26 is thrown back by the tension of the spring 105 on said rock-shaft, Fig. 7, to the position 90 shown in Fig. 1. At the time the lay comes to the end of its forward motion and the rock-shaft 26 has been thus turned to its normal position by the action of the spring 105, the lever 30 on the end of said rock-shaft is 95 thereby moved from the position shown in Fig. 6 to the position shown in Fig. 5 and by connections 31 34 raises the switch 36, so that it clears the groove 38 39 of the switch-block 37. Now when the lay moves back, the roller 100 45 runs in said groove 38 39. The shuttle in the right-hand shuttle-box is struck by the picker and picker-stick therein and thrown through the shed of the warps into the left-hand shuttle-box. When the shuttle enters 105 the left-hand shuttle-box, the binder 79 of said shuttle-box is forced back against the top end of the binder-finger 78, thus forcing down the bent end 77 of the binder-shaft 62. The rocking of the binder-shaft thus caused 110 raises the dagger 7 above the path of the dagger-slide 106. When the shuttle has entered the left-hand shuttle-box and the lay moves forward, the weft lies in the path of the weft-fork 19, thus depressing the lower end of the 115 weft-fork and raising the front hooked end thereof out of the path of motion of the bent lever 16, and as the lay finishes its forward motion the weft is beaten up in the shed of the warps by the reeds 401 in the usual manner. 120 In order to facilitate the placing of the fresh shuttle from the reservoir 55 into the adjacent shuttle-box, I pivotally connect the link-bar 70 to the pusher 72 at a point 71 considerably to the left of the middle of the pusher 125 72, as shown in Figs. 10 and 21, and also place projections 107 108 on the ends thereof. On the ends of the reservoir 55 and near the bottom thereof are flanges 109 110. When the link-bar 70 moves forward, as already described, as it is much nearer the inner end than the outer end of the pusher, said inner end advances more rapidly, and as a result 130 the inner end of the fresh shuttle supplied to

the right-hand shuttle-box is crowded into the shuttle-box first, as illustrated in Figs. 21 and 22, its sharp end forcing its way to overcome the binding pressure of the swell, and this continues until the projection 107 of the pusher 72 comes into contact with the flange 109 of the reservoir 55. The further advance of the link-bar 70 then pushes forward the outer end of said pusher 72 until its projection 108 strikes against the flange 110 of the reservoir 55, thus completing the proper transfer of the fresh shuttle from the reservoir to the shuttle-box, as illustrated in Fig. 19. In this manner the shuttle acts like a wedge to force the binder or swell of the shuttle-box to allow the entrance of the shuttle into the shuttle-box. (See Fig. 22.) The shuttle-boxes when rotated to their vertical position stand up in front of the path of the picker and above the same.

The loose ends of the weft-threads from the several shuttles in the reservoir 55 are fastened by winding them around the bent upper end 59 of the lever 57 on the front of the reservoir, as shown in Figs. 5, 8, and 10. Therefore whenever a fresh shuttle has been supplied to the right-hand shuttle-box and said shuttle has been thrown by the picker from said box there is a portion of its weft 25 which extends from the end 59 of the lever 57 into, through, and out of the said shuttle-box. This weft-thread is cut off at the right-hand selvage of the cloth by the following mechanism: On the rock-shaft 41 is a collar-cam 30 111, secured in place by the screw 112 and having four notches on the edge thereof, one shown at 113 and one of the same size and shaped diametrically opposite on the same side, one shown at 114 and one of the same size 35 40 and shape diametrically opposite on the same side. (See Figs. 10, 23, and 25.) The notch 114 and that diametrically opposite are, however, much smaller and more shallow than the notch 113. A ratchet-cam 115 is loosely 45 mounted on the shaft 41 and has two diametrically opposite arms 116 117 extending therefrom, four ratchet-teeth 118 ninety degrees apart, and two diametrically opposite cam projections 119. A pawl or catch 120 is pivoted 50 at 121 on a bracket beneath the lay, Figs. 11, 12, 13, 23, 24, 25, 26, and 27, and has a downward projection 122, to which a spiral spring 123 is attached. A ratchet-arm 124 is loosely 55 mounted on the rock-shaft 41. A spiral spring 125 surrounds said shaft and has one end bearing against a fixed collar, as shown at 126 and the other end bearing against the ratchet-arm 124. A bunter 127 is fastened to 60 and projects from the breast-beam 6. A pawl 128 is pivoted at 129 to the side of the ratchet-arm 124, (see Figs. 10, 23, 24, 25, 26, and 27,) which is kept in its normal position by the spring 130. A lever 131 is also mounted on the pivot 121, and the spring 123 is fastened 65 thereto, which extends from the downward projection 122. The lever 131 is pivotally connected at one end, as shown at 132, to the

link 133, and said link is pivotally connected at 134 to the lower handle of a pair of shears 135. The upper handle of the shears is pivoted at 136 to a fixed support on the back of the lay. A spiral spring 137 is fastened at its upper end to the lever 131 and at its lower end to a fixed support. A bracket 138 projects from the lay, as shown in Fig. 11. The operation of this cutting device is as follows: When the weft-fork 19 has been engaged, as hereinbefore described, by the upper end of the bent lever 16, the rock-shaft 41, through the intermediate connections, is partially rotated, and the collar-cam 111, fixed on said shaft, turns with it. As the cam projection 119 of the ratchet-cam 115 is engaged in the notch 113 of the fixed collar-cam 111 (being held therein by the pressure of the spiral 80 spring 125 on the rock-shaft 41) this partial rotation of the fixed collar 111 communicates its motion to the ratchet-cam 115 and moves it from the position shown in Fig. 11 to the position shown in Fig. 12, whereupon the holding-pawl 120 by the force of the spring 123 engages the end of the projecting-arm 116, as seen in Fig. 12, and prevents any return movement of the cam 115 when the rock-shaft rotates back to its former position. (See 85 also Figs. 23 to 29, inclusive.) Then as the lay moves forward the rock-shaft 41, partially rotating as already explained, turns the collar-cam 111 with it and forces sidewise the ratchet-cam 115 by causing the projection 119 of said cam 115 to move out of the notch 113 of the fixed cam 111. This lateral movement of the ratchet-cam 115 gives a lateral movement to the adjacent loosely-mounted ratchet-arm 124, and thereby compresses the spiral 90 spring 125, which surrounds the rock-shaft 41. This lateral movement of the ratchet-arm 124 on the shaft 41 brings said ratchet-arm into line with the bunter 127 of the breast-beam 6. The ratchet-arm 124 in so rising 95 moves the pawl 128, pivoted thereon, which catches the nearest tooth 118 of the ratchet-cam 115 and moves the projecting arm 116 thereof one-fourth of a revolution from the position shown in solid lines in Fig. 11 to the position shown in dotted lines in Fig. 12, and thereby the sharp edge of the cam projection 119 of the ratchet-cam 115 is brought opposite to the shallow notch 114 of the collar-cam 111 and is seated therein by the force of 100 the spiral spring 125. Then as the lay moves backward the ratchet-arm 124 descends to its former position, being forced down again by the torsional pressure of the spiral spring 125, whose end is inserted and secured in the side 105 of the ratchet-arm 124. When the lay moves 110 forward the next time, the shuttle has entered the left-hand shuttle-box and carried the weft-thread of the newly-supplied shuttle across. The ratchet-arm 124, now being 115 in line with the bunter 127, is again raised by its contact therewith and by the pawl 128, which engages in the next ratchet-tooth 118 of the ratchet-cam 115, rotates said 120 125 130 135 140

ratchet-cam 115 a quarter-turn, which brings the projecting arm 116 thereof from the position shown in dotted lines in Fig. 12 to the position shown in Fig. 13, whereupon the cam 5 projection 119 of the ratchet-cam 115 is thus brought opposite that notch of the fixed collar-cam 111 which is diametrically opposite the notch marked 113 on the drawings. The result of these movements is that the projecting arm 116 in making the quarter-revolution last mentioned acts as a wiper, and by bearing down on the lever 131 raises, by its connected link 133, the lower handle of the shears 135. The blades of the shears (between which 10 the weft-thread of the newly-supplied shuttle lies) are thereby thrust through the reeds 401 and close, thus cutting said weft-thread, as will be seen by examination of Figs. 12 and 13. At the end of this cutting operation the 15 projection 116 of the ratchet-cam 115 has cleared the end of the lever 131, whereupon the spring 137 returns the handles of the shears 135 to their former position, thus withdrawing the blades of the shears behind the 20 reed 401, and at the same time the ratchet-arm 124 is forced to its normal position by the spring 125 on the rock-shaft 41 and out of the line of the bunter 127, as the cam projection 25 119 of the ratchet-cam 115 is pressed by said 30 spring into that notch of the fixed collar-cam 111 which is opposite to the notch marked 113 on the drawings, where it remains until the weft-thread of the operating-shuttle is broken or exhausted and another weft-thread 35 is newly supplied by a fresh shuttle, the projecting arm 117 of the cam 115 having been brought to the position shown in Fig. 11 as occupied by the arm 116—that is, the motion of the arms 116 117 and the cam 115, from 40 which they project, being intermittently rotary in one direction when the shaft 41 rocks, while the movement of the ratchet-arm 124 is an intermittently oscillating movement during the rocking of said shaft. When the 45 weft-thread of the newly-supplied shuttle was first laid by the passage of said shuttle through the shed, the end of said thread which had been wound on the bent end 59 of the thread-lever 57 of the reservoir 55 pulled said end 50 of the lever 57 down and so raised its short weighted end. The cutting of said weft-thread, as just described, allows the thread-lever 57 to resume its normal position by means of its weighted end, which in descending 55 elevates the upper end of said lever and pulls the cut-off end of the weft-thread out of the shuttle-box and away from the lay.

In order to prevent the spent shuttle from rebounding out of the pan 80 when it is forced 60 therein by the push-plate 93, two springs or bars 139 are provided, each of which is mounted loosely upon a rod 140 in an elongated opening or slot in the end of said spring. The rods 140 are secured on the top of the guide- 65 plate 92 of the pan 80, and the springs or bars are of such length that they are directed angularly backward when their bottoms touch

the bottom of the pan. The springs or bars 139 offer no resistance to the shuttle as it passes into the pan; but as they cannot be 70 swung out in a forward direction they prevent the shuttle when once in the pan from moving out of it again. (See Fig. 16.)

The cloth when woven passes, as usual, over the breast-beam 6, around the sand-roller 75 8, and is wound upon the cloth-roller 9. The sand-roller 8 has upon it the gear 10, which rotates therewith, and the gear 10 meshes with the pinion 141, which is mounted on the same shaft as the ratchet-gear 11. The feeding-pawl, by which the ratchet-gear 11 is intermittently moved, is shown at 142. It is pivotally mounted on the bent lever 16, as appears at 143, Fig. 1, and is provided with a weight or counterpoise 144 on its upper short 80 bent end. Its lower end engages with the ratchet-gear 11. Said feeding-pawl rises and falls by reason of its connection with the vibrating bent lever 16, and so advances the ratchet-gear 11 tooth by tooth and causes the 85 winding of the cloth upon the cloth-roller 9. The holding-pawl 145 is shown in Fig. 1. It is engageable with the ratchet-gear 11 and is pivotally mounted, as at 146, to the loom-frame. Its upper end is bent, as shown in 90 Fig. 1, and a presser or lever 147, fastened to the rock-shaft 26, bears against said holding-pawl whenever the shaft 26 is rocked in consequence of the forward movement of the 95 sliding plate 21 communicated to the upper end of the lever 25, as already explained. All this construction is well known and operates in the manner heretofore usual; but this cloth-winding mechanism is so operated in relation to the shuttle-transferring mechanism that when the weaving-shuttle on the lay has exhausted or broken its filling-thread, although the feeding-pawl 142 continues its movements, as before, the holding-pawl 145, being lifted out of engagement with the ratchet-gear 11, because of the rocking of the shaft 100 26, produced as above explained, does not hold the ratchet-gear 11 in the position to which it has been advanced by the feeding-pawl 142. Consequently the cloth-roller 9 105 by the tension of the cloth between it and the breast-beam 6 is rotated back as much as it has been advanced, and so no cloth is wound during the one pick when and while the spent shuttle is removed from the left-hand shuttle-box into the shuttle-receiving pan 80 and the fresh shuttle is moved from the shuttle-reservoir 55 into the right-hand shuttle-box, 110 as hereinbefore specified.

In Figs. 14 and 15 is shown a modified form 115 of the shuttle-ejecting means, in which the push-plate 93, sliding rod 88, and all the mechanism between them and the binder-finger 78 (shown in Figs. 1, 2, 3, 4, 7, and 9) is dispensed with. In this construction the open 120 bottom of the shuttle-box is presented to the front of the pan 80, and the momentum of the shuttle as the lay 4 moves forcibly backward 125 ejects the shuttle from the box into the pan as

soon as the lay reaches the extreme limit of its rearward movement.

In Figs. 2 and 3 is shown a modified form of the vertical rock-shaft 83 and means for moving it. Here the vertical rock-shaft (marked in said figures 83') is mounted at its bottom in a bracket from the loom-frame and is surrounded by a spiral spring 148 to give return rotation. A sleeve is mounted on said vertical rock-shaft 83', as indicated in said figures by dotted lines, and an arm 84 extends angularly from said sleeve, as shown there by dotted lines. The bent end 77 of the binder-shaft 62 is in line to press against said arm, as indicated in Fig. 3, so partially rotating the shaft 62 and operating the sliding rod 88 and connections for removing the spent shuttle, as already described.

I claim as a novel and useful invention and desire to secure by Letters Patent—

1. In a loom, the combination of a lay having a movable shuttle-box, a filling-detector, a stationary shuttle-reservoir independent of the lay and located in a position vertically above the end of the lay when the lay reaches the limit of its backward movement, a shuttle-transferrer operative upon the failure of the filling-thread in the shed to move forward toward the breast-beam the lowest shuttle in the reservoir and place the same in said shuttle-box, and connections between the filling-detector and shuttle-box adapted to move said shuttle-box into position for the reception of said shuttle as the lay completes its backward motion, substantially as specified.

2. In a loom, the combination of a lay having a movable shuttle-box, a filling-detector, a stationary shuttle-reservoir independent of the lay and located in a position vertically above the end of the lay when the lay reaches the limit of its backward movement, a shuttle-transferrer operative upon the failure of the filling-thread to move a shuttle from said reservoir directly into the shuttle-box, and means adapted to move the shuttle-box into position for the reception of said shuttle and to return said shuttle-box to its normal position upon the lay, substantially as described.

3. In a loom, the combination of a lay having a movable shuttle-box, a filling-detector, a stationary shuttle-reservoir independent of the lay and located in a position vertically above the end of the lay when the lay reaches the limit of its backward movement, a shuttle-transferrer operative upon the failure of the filling-thread to move a shuttle from said reservoir into the shuttle-box as the lay completes its backward motion, and means adapted to move the shuttle-box so as to place the shuttle therein contained in operative position upon the lay during the next forward beat of the lay, substantially as shown.

4. In a loom, the combination of a lay having a movable shuttle-box, a filling-detector, a stationary shuttle-reservoir independent of the lay and located in a position vertically above the end of the lay when the lay reaches

the limit of its backward movement, a shuttle-transferrer operative upon the failure of the filling-thread to move a shuttle forward through the front of the shuttle-reservoir through the bottom of the shuttle-box, and means adapted to move the shuttle-box so as to place the shuttle therein contained in operative position upon the lay, substantially as specified.

5. In a loom, the combination of a lay having a movable shuttle-box, a filling-detector, stationary means independent of the lay to support one or more shuttles, a shuttle-transferrer located at the rear of the shuttle-supporting means and adapted to engage and transfer a shuttle from the shuttle-supporting means to the shuttle-box, together with means adapted to move the shuttle-box so as to place the shuttle therein contained in operative position, during the next forward movement of the lay, substantially as set forth.

6. In a loom, the combination of a lay having a movable shuttle-box, a filling-detector, a stationary shuttle-reservoir mounted above the plane of the lay and independent of the lay, a shuttle-transferrer mounted movably upon a rearward projection of the shuttle-reservoir, and means operative upon the failure of the filling-thread to actuate the transferrer and move a shuttle forward from the shuttle-reservoir into the shuttle-box, substantially as shown.

7. The combination of a shuttle-transferrer and a shuttle-reservoir for looms, the latter comprising an upright box, open at its top, lower front, lower rear and middle front and a projection at its lower rear end, which is adapted to support said shuttle-transferrer, substantially as specified.

8. In a loom, the combination of a lay having a movable shuttle-box, a stationary shuttle-reservoir independent of the lay and open at its top, lower front, lower rear and middle front, yielding detents at its lower front ends arranged to prevent the lowest shuttle from displacement in the shuttle-reservoir by the vibrations of the loom, a rocker-arm for fastening the ends of the wefts which extend from the shuttles in the shuttle-reservoir, and a shuttle-transferrer at the lower rear end of the shuttle-reservoir and adapted to engage the lowest shuttle in the shuttle-reservoir and to force the same therefrom into the shuttle-box upon failure of the filling-thread, substantially as described.

9. The combination of a shuttle-reservoir, a shuttle-box and a shuttle-transferrer movably mounted in the rear of the shuttle-reservoir and adapted to engage the lowest shuttle in said reservoir and move said shuttle forward through the front of the reservoir and through the bottom of the shuttle-box as the lay completes its backward motion, substantially as described.

10. The combination of a shuttle-box having a binder, a shuttle-transferrer, and means to operate the same upon failure of the filling-

thread so as to place one end of a shuttle in the shuttle-box to displace the free end of the binder and while holding said end of the shuttle in the shuttle-box to press the other end of the shuttle therein, substantially as shown.

11. In combination with a shuttle-box, a shuttle-transferrer, means adapted to operate the transferrer so that when transferring a shuttle to the shuttle-box said shuttle enters the shuttle-box at an angle with the opening in the shuttle-box and means adapted to move said shuttle after it has so entered the shuttle-box into operative position therein, substantially as set forth.

12. In a loom, adapted to renew its supply of filling-thread when necessary, the combination of a lay having a movable receiving shuttle-box at one end and a movable rejecting shuttle-box at the other end, a stationary shuttle-reservoir independent of the lay and adjacent to the receiving shuttle-box when the lay is at the end of its rearward motion and containing a supply of shuttles each provided with filling-thread, a stationary shuttle-receiving pan independent of the lay and adjacent to the rejecting shuttle-box when the lay is at the end of its rearward motion, a filling-detector, and means adapted to effect the ejection of the spent shuttle from the last-named shuttle-box into said receiving pan and the transfer of a fresh shuttle from the shuttle-reservoir to the receiving shuttle-box, which means derive motion from the filling-detector and operate simultaneously, substantially as specified.

13. In a loom, the combination of a lay having a movable shuttle-box, a filling-detector, a stationary shuttle-receiving pan independent of the lay located in a plane above that of the shuttle-box, projecting over the shuttle-box and adjacent thereto, and connections between the filling-detector and the shuttle-box adapted to move said shuttle-box into the plane of said pan and to eject the shuttle from the shuttle-box into said pan as the lay completes its backward movement, substantially as specified.

14. In a loom, the combination of a lay having a movable shuttle-box with a binder, a filling-detector, a stationary shuttle-receiving pan independent of the lay and adjacent to the shuttle-box, connections between the filling-detector and shuttle-box adapted to move said shuttle-box in the arc of a circle, and means adapted to release the pressure of the binder on the shuttle in the shuttle-box as the lay completes its backward movement, substantially as described.

15. In a loom, the combination of a lay having a movable shuttle-box, a filling-detector, a stationary receiving pan independent of the lay, located above the plane of the shuttle-box and adjacent to the shuttle-box, a shuttle-transferrer, and connections between the filling-detector and the shuttle-box adapted to move the shuttle-box into position for the transferrer to remove the shuttle from the

shuttle-box as the lay completes its backward motion, substantially as shown.

16. In a loom, the combination of a lay having a movable shuttle-box provided with a binder, a filling-detector, a stationary shuttle-receiving pan independent of the lay and adjacent to said shuttle-box, a shuttle-transferrer mounted movably on the receiving-pan, and connections between the filling-detector and the shuttle-box adapted to move said shuttle-box in the arc of a circle, to move the binder out of position and to move the transferrer into the shuttle-box and eject the shuttle therefrom and also to return said shuttle-box to its normal position upon the lay during the forward motion of the lay, substantially as specified.

17. In a loom, the combination of a lay having a movable shuttle-box, a filling-detector, a stationary receiving-pan independent of the lay, a shuttle-transferrer, and means operative upon the failure of the filling-thread to move said transferrer so as to transfer a shuttle from the shuttle-box into the receiving-pan, substantially as described.

18. In a loom provided with means to renew its supply of filling-thread when necessary, the combination of a lay, a movable shuttle-box thereon, open at its bottom, shuttle-expelling mechanism adapted to compel the exit of a shuttle through the bottom of the shuttle-box in a plane above the normal plane of the shuttle-box, a filling-detector, and means intermediate between it and the shuttle-box to operate said shuttle-box and said shuttle-expelling mechanism, upon failure of the filling, substantially as shown.

19. In a loom provided with means to renew its supply of filling-thread when necessary, the combination of a lay, a picker and picker-stick, a movable shuttle-box thereon open at its top and bottom, a filling-detector and means between said detector and shuttle-box operative upon failure of the filling-thread to move the shuttle-box so as to place the shuttle therein contained above and to one side of the picker and to remove said shuttle from the shuttle-box, substantially as described.

20. In a loom provided with means to renew its supply of filling-thread when necessary, the combination of a lay, a picker and picker-stick, a movable shuttle-box upon the lay and having a binder, a filling-detector, and means between the filling-detector and shuttle-box operative upon failure of the filling-thread to move the shuttle-box so as to place the shuttle contained therein above and to one side of the picker and release the pressure of the binder upon the shuttle so as to eject the shuttle from the shuttle-box, as the lay completes its backward motion, substantially as specified.

21. In a loom, the combination of a lay, a vertically-movable shuttle-box comprising two longitudinal sides and an end and provided with a binder, a flat spring secured to the shuttle-box and bearing against the

- binder, an inward projection from the top edge of the shuttle-box, and a movable inward projection from the bottom edge of the shuttle-box slightly below said bottom edge and extending beneath the path of motion of the shuttle for the purpose of supporting the shuttle in the shuttle-box while said shuttle-box is rising from the lay, substantially as described.
- 10 22. In a loom provided with means to supply a fresh shuttle upon failure of the filling-thread, the combination of a lay, a picker and picker-stick, a filling-detector, a vertically-movable shuttle-box, having a flat spring fastened to its side and projecting within the shuttle-box and located in a line slightly below the bottom of the shuttle-box, and a cam fastened on the lay and adapted to hold the projecting end of the spring below the path of motion of the shuttle and retain the shuttle in the shuttle-box against the pressure of the picker on the point of the shuttle while the shuttle-box is rising from the lay and to allow said spring to withdraw from beneath the shuttle after the shuttle is raised above the picker, substantially as specified.
- 15 23. In a loom provided with means to supply a fresh shuttle upon failure of the filling-thread, the combination therewith of a shuttle-receiving pan or reservoir fastened to the side frame or arch of the loom above the normal path of motion of the ejecting shuttle-box projecting over said shuttle-box and adjacent thereto and adapted to receive a spent shuttle when ejected from the shuttle-box, substantially as specified.
- 20 24. In a loom provided with means to renew its supply of filling-thread when necessary, the combination of a receiving pan or reservoir fastened to the frame of the loom above the normal path of motion of the shuttle-box and adjacent thereto, and a movable ejector supported on said pan or reservoir, and operative upon failure of the filling-thread to renew the spent filling-carrier from the shuttle-box into the receiving pan or reservoir, substantially as described.
- 25 25. In a loom, the combination of filling-supplying mechanism and mechanism operative upon failure of the filling to effect the delivery of a fresh supply of filling at one end of the lay and to eject the spent filling-carrier at the other end as the lay completes its backward motion, substantially as set forth.
- 30 26. In a loom, the combination of filling-supplying mechanism, and mechanism operative upon failure of the filling to effect the delivery of a fresh supply of filling through the bottom of the shuttle-box into said shuttle-box at one end of the lay and to eject the spent filling-carrier through the bottom of the shuttle-box at the opposite end of the lay as the lay completes its backward motion, substantially as described.
- 35 27. In a loom provided with means to furnish a fresh supply of filling-thread when necessary, the combination of a lay, a push-plate and means to operate the same, a movable shuttle-box on the lay, a filling-detector and means actuated thereby and operative upon failure of the filling-thread to rotate the shuttle-box one-fourth of a revolution for the purpose of enabling said push-plate to enter said shuttle-box, and positively eject the filling-carrier through the bottom of the shuttle-box as the lay completes its backward motion substantially as shown.
- 40 28. In a loom provided with means to furnish a fresh supply of filling-thread when necessary, the combination of a lay, a push-plate and means to operate the same, a movable shuttle-box on the lay, a filling-detector and means to rotate the shuttle-box one-fourth of a revolution for the purpose of enabling said push-plate to enter said shuttle-box and positively eject the spent filling-carrier therefrom through the bottom of the shuttle-box as the lay completes its backward motion, and means adapted to return said shuttle-box to its normal position as the lay comes forward, substantially as specified.
- 45 29. In a loom, the combination of a lay, a movable shuttle-box on each end of the lay, a reservoir properly supported in the rear of one of said shuttle-boxes but independent of the lay, a receiving-pan properly supported in the rear of the other shuttle-box but independent of the lay, and filling-supplying mechanism operative upon failure of the filling to effect the delivery of a fresh supply of filling from said reservoir into the shuttle-box adjacent thereto and to eject the spent filling-carrier from the opposite shuttle-box into the receiving-pan as the lay completes its backward motion and to return both said shuttle-boxes to their normal position as the lay comes forward, substantially as shown.
- 50 30. In a loom, the combination of a lay, a filling-detector, a movable shuttle-box on each end of the lay, pivoted in suitable bearings attached to the lay, and mechanism operative upon failure of the filling to move said shuttle-boxes ninety degrees upon their bearings while the lay is moving in one direction and to return them to their normal position while the lay is moving in the opposite direction, substantially as described.
- 55 31. In a loom, the combination of a lay, a filling-detector, a movable shuttle-box at each end of the lay mounted upon suitable bearings attached to the front of the lay, and means in connection with the filling-detector to simultaneously move both said shuttle-boxes one-fourth of a revolution during the backward motion of the lay and to return said shuttle-boxes to their normal position during the forward movement of the lay, substantially as specified.
- 60 32. In a loom provided with means to supply a fresh shuttle upon failure of the filling-thread, the combination therewith of a lay, a push-plate and means to operate the same, a movable ejecting shuttle-box pivotally mounted at or near its two front lower corners in

suitable bearings attached to the lay, and means operative on such failure of the filling to change the position of said shuttle-box while retaining the spent shuttle therein for the purpose of enabling the push-plate to enter said shuttle-box and positively to eject the said shuttle from the said shuttle-box when the latter has reached the proper position therefor, as the lay completes its backward motion, substantially as specified.

33. In a loom, the combination of a lay, a movable shuttle-box pivotally mounted on suitable bearings upon the lay and having a spring-pressed binder pivoted to its rear side and normally pressing inwardly, an inward projection at the top of the shuttle-box adapted to guide the shuttle when moving into the shuttle-box, a stationary shuttle-reservoir properly mounted on the loom-frame and independent of the moving parts of the loom, means operative upon the failure of the filling-thread to move the shuttle-box to the shuttle-reservoir, and means to transfer a shuttle from said reservoir to the shuttle-box as the lay completes its backward motion, substantially as specified.

34. In a loom adapted to renew its supply of filling when necessary, the combination of a shuttle-reservoir and a rocking arm pivoted thereto, a shuttle in said reservoir, and a weft-thread from said shuttle to the end of said rocking arm, substantially as shown.

35. In a loom adapted to renew its supply of filling when necessary, the combination of a filling catch or arm pivoted to a stationary part of the loom, a weft-carrier, and a weft-thread therefrom extending and fastened to said catch or arm and adapted to rock said catch or arm on its axis by the tension of said weft-thread, substantially as set forth.

36. In a loom adapted to renew its supply of filling when necessary, a shuttle-reservoir, a filling catch or arm pivotally mounted adjacent to the shuttle-reservoir, means tending to keep the upper end of said arm in a raised position, a shuttle, and a weft-thread from the shuttle to the upper end of said catch or arm, substantially as described.

37. In a loom provided with means to supply a fresh shuttle upon failure of the filling-thread, the combination of a lay, a reed on said lay, a shuttle having a weft-thread whose end is attached to a proper support, a pair of shears pivotally mounted in suitable bearings upon the lay behind the reed out of the path of motion of the shuttle and adapted to be operated upon failure of the filling-thread, a weft-fork and means intermediate between the weft-fork, and shears adapted to move the shear-blades through the reed for the purpose of cutting the said weft-thread from the selvage of the cloth as the lay completes its forward motion, substantially as specified.

38. In a loom provided with means to supply a fresh shuttle upon failure of the filling-thread, the combination of a lay, a shuttle movable thereon, a weft-fork, a pair of shears

mounted in suitable bearings upon the lay out of the path of motion of the shuttle and means intermediate between said weft-fork, and shears adapted to operate the latter for the purpose of cutting the weft-thread projecting from the selvage of the cloth as the lay completes its forward motion, substantially as specified.

39. In a loom provided with means to supply a fresh shuttle upon failure of the filling-thread, the combination of a lay, a pair of shears pivotally mounted thereon in suitable bearings in the rear of the reed out of the path of motion of the shuttle, a weft-fork, a movable thread-lever mounted on a fixed support, means which tend to elevate the end of said lever, a shuttle having a weft-thread whose end is fastened to the upper end of said thread-lever, and means intermediate between the weft-fork and the shears adapted to operate said shears upon the failure of the filling for the purpose of cutting the said weft extending from the selvage of the cloth as the lay completes its forward motion, substantially as described.

40. In a loom, the combination of a lay and a shuttle-box movable thereon, having a front side, a rear side and one closed outer end, but open at top and bottom and so placed on the lay that when the shuttle-box is in proper operative position the lay itself constitutes the bottom of the shuttle-box, but when the shuttle-box is in proper position for the reception of a fresh shuttle said front side and rear side thereof extend in planes parallel with the top of the lay, substantially as shown.

41. In a loom, the combination of a lay, a shuttle-box having an open bottom, a front side, a rear side and one closed end and provided with earpieces on its front side at or below the central longitudinal line thereof, by which earpieces it is pivotally connected with the lay, said shuttle-box normally resting with its open bottom upon the lay but rotatable to a position in which its front side and rear side are in planes parallel with the top of the lay, substantially as specified.

42. In a loom, the combination of a lay, a shuttle-reservoir mounted on a fixed support in the rear of the lay independent of the lay, and having an opening in front at the bottom thereof, a vertically-rotatable shuttle-box mounted pivotally on the lay and having an open bottom, the edges of which normally rest upon the lay but which open bottom is contiguous to the opening in the reservoir, when the shuttle-box has been rotated a quarter-revolution, means adapted to move a shuttle from said reservoir through the opening in the reservoir and through the open bottom of the shuttle-box, into said shuttle-box and a spring-pressed binder in the shuttle-box to hold said shuttle in position when moved therein, substantially as specified.

43. In a loom, the combination of a lay, a shuttle-receiving pan having an open front and mounted upon a fixed support in the rear

of the lay and independent thereof, a vertically-rotatable shuttle-box mounted pivotally on the lay and having an open top and an open bottom, the edges of which bottom normally rest upon the lay, but which open bottom is contiguous to the open front of said pan when the shuttle-box has been rotated a quarter-revolution, and means adapted to positively move a shuttle from said shuttle-box into said receiving-pan when said shuttle-box is raised to the elevated position last aforesaid, substantially as shown.

44. In a loom, the combination of a lay, a shuttle-reservoir mounted on a fixed support in the rear of the lay, independent of the lay and having an opening in front at the bottom thereof, a shuttle-receiving pan having an open front and mounted on a fixed support in the rear of the lay and independent thereof, two vertically-rotatable shuttle-boxes mounted pivotally on the lay adjacent, respectively, to said reservoir and pan, each of which shuttle-boxes has an open top and an open bottom with the bottom edges normally resting upon the lay but which open bottoms are directed rearwardly when the shuttle-boxes have been rotated a quarter-revolution, means adapted to rotate said shuttle-boxes in unison, a reciprocally-movable pusher adapted to move a shuttle from said reservoir into a contiguous shuttle-box and a reciprocally-movable pusher adapted to move a shuttle from the opposite shuttle-box, into the contiguous receiving-pan, all operating substantially as shown and for the purpose specified.

35 45. In a loom, the combination of a lay, a shuttle-reservoir mounted on a fixed support in the rear of the lay, independent of the lay and having an opening in both front and rear at the bottom thereof, a vertically-rotatable shuttle-box pivotally mounted on the lay and having an open top and an open bottom with the bottom edges normally resting upon the lay but which open bottom is directed rearwardly when the shuttle-box has been rotated a quarter-revolution, and a reciprocally-movable pusher adapted and arranged to move a shuttle from said reservoir into the shuttle-box, when the shuttle-box is raised to the elevated position last aforesaid, substantially as described.

55 46. In a loom, the combination of a lay, a shuttle-receiving pan having an open front and mounted upon a fixed support in the rear of the lay and independent of the lay, a vertically-rotatable shuttle-box mounted pivotally on the lay and having an open top and an open bottom with the bottom edges normally resting upon the lay but which open bottom is directed rearwardly when the shuttle-box has been rotated a quarter-revolution and a reciprocally-movable pusher adapted and arranged to move a shuttle from said shuttle-box into said receiving-pan when the shuttle-box is raised to the elevated position last aforesaid, substantially as specified.

65 47. In a loom, the combination of a lay, a shuttle-reservoir mounted on a fixed support

in the rear of the lay, independent of the lay and having an opening in front and in the bottom thereof, a shuttle-receiving pan having an open front and mounted on a fixed support in the rear of the lay and independent thereof, two vertically-rotatable shuttle-boxes mounted pivotally on the lay adjacent, respectively, to said reservoir and pan, each of which shuttle-boxes has an open top and an open bottom with the bottom edges normally resting upon the lay but which open bottoms are directed rearwardly when the shuttle-boxes have been rotated a quarter-revolution, means adapted to rotate said shuttle-boxes in unison, a reciprocally-movable pusher adapted to move a shuttle from said reservoir into a contiguous shuttle-box and a reciprocally-movable pusher adapted to move a shuttle from the opposite shuttle-box, into the contiguous receiving-pan, all operating substantially as shown and for the purpose specified.

48. In a loom having a receptacle for shuttles independent of the lay, the combination therewith of a lay, a shuttle-box pivotally mounted upon the lay upon suitable bearings so as to vertically rotate a quarter-revolution, a gear fastened to the shuttle-box and concentric with the pivotal mounting of said shuttle-box, a gear mounted on a support upon the lay and engaging the first-named gear, and means adapted to rotate the last-named gear, substantially as and for the purpose specified.

49. In a loom, the combination of a lay, a shuttle-reservoir having an opening in front at the bottom thereof and mounted on the frame of the loom behind the lay, a shuttle-receiving pan having an open front and mounted on the frame of the loom behind the lay, a rod properly mounted at its ends on the lay and extending longitudinally in front of the lay and parallel thereto, a shuttle-box mounted on said rod through earpieces on the lower front edge thereof adjacent to the shuttle-reservoir, a shuttle-box mounted on said rod through earpieces on the lower front edge thereof adjacent to the shuttle-receiving pan, each shuttle-box having an open top and an open bottom, a gear fastened to each of said shuttle-boxes and mounted upon said rod, a rock-shaft properly mounted on the lay parallel with said rod, means adapted to rock said shaft, two gears fastened on said rock-shaft and engaging, respectively, with said shuttle-box gears, a reciprocally-movable pusher adapted and arranged to move a shuttle from said reservoir into the contiguous shuttle-box, and a reciprocally-movable pusher adapted and arranged to move a shuttle from the opposite shuttle-box into the contiguous receiving-pan, substantially as specified.

50. In a loom, the combination of a lay, a shuttle-reservoir having an opening in front at the bottom thereof and mounted on the loom-frame behind the lay, a shuttle-receiving

ing pan having an open front and mounted on the loom-frame behind the lay, a rod properly mounted at its ends on the lay and extending longitudinally in front of the lay and parallel thereto, a shuttle-box mounted on said rod through earpieces on the lower front edge thereof adjacent to the shuttle-reservoir, a shuttle-box mounted on said rod through earpieces on the lower front edge thereof adjacent to the shuttle-receiving pan; each shuttle-box having an open top and an open bottom, a gear fastened to each of said shuttle-boxes and mounted upon said rod, a rock-shaft properly mounted on the lay parallel with said rod, two gears fastened on said rock-shaft and engaging, respectively, with said shuttle-box gears, a reciprocating pusher arranged and adapted to move a shuttle from the shuttle-reservoir into the contiguous shuttle-box, a reciprocating pusher arranged and adapted to move a shuttle from the opposite shuttle-box into the receiving-pan, an oscillating weft-fork, and means intermediate between said weft-fork and shaft adapted to rock said shaft, substantially as shown.

51. In a loom, the combination of a lay, a shuttle-reservoir having an opening in front at the bottom thereof and mounted on the loom-frame behind the lay, a shuttle-receiving pan having an open front and mounted on the loom-frame behind the lay, a rod properly mounted at its ends on the lay and extending longitudinally in front of the lay and parallel thereto, a shuttle-box mounted on said rod through earpieces on the lower front edge thereof adjacent to the shuttle-reservoir, a shuttle-box mounted on said rod through earpieces on the lower front edge thereof adjacent to the shuttle-receiving pan, each shuttle-box having an open top and an open bottom, a gear fastened to each of said shuttle-boxes and mounted upon said rod, a rock-shaft properly mounted upon the lay parallel with said rod, two gears fastened on said rock-shaft and engaging, respectively, with said shuttle-box gears, a reciprocating pusher adapted to move a shuttle from the shuttle-reservoir into the contiguous shuttle-box, a reciprocating pusher adapted to move a shuttle from the opposite shuttle-box into the receiving-pan, an oscillating weft-fork adapted to take a horizontal position upon the failure of the filling-thread, a sliding plate to which the weft-fork is pivoted, a shaft driven by power and provided with a cam, a bent lever pivotally mounted on the loom-frame and having its lower end in contact with said cam and its upper end engageable with said weft-fork when the latter is horizontal upon the failure of a filling-thread, a rock-shaft properly mounted and having a lever-arm movable by the sliding plate, a switch-block with a lower groove which is substantially horizontal and with a slot which is angularly inclined upward, a switch pivotally mounted and adapted to close either said groove or slot, a lever-arm on the last-named rock-shaft, a link con-

nexion between the last-mentioned lever-arm and said switch, and an arm extending from one of the gears last mentioned and having at its end a friction-roller movable in said groove or slot according to the position of said switch, all combined and operating substantially as shown and for the purpose specified.

52. In a loom, the combination of a lay, a shuttle-receiving pan supported on the loom-frame behind and independent of the lay, a shuttle-box rotatably mounted on said lay and having an open top and an open bottom, means adapted to rotate the shuttle-box a quarter-revolution, a shutter hinged to the edge of the shuttle-box and extending in the same direction, which shutter in its normal extended position is parallel with the top of the lay but is movable on its hinges to a position at a right angle with its normal plane, means adapted to move said shutter from its normal position to its angular position, a spring adapted to return said shutter to its normal position when free, and means adapted to move a shuttle from the shuttle-box to the receiving-pan, substantially as specified.

53. In a loom, the combination of a lay, a shuttle-reservoir supported on the loom-frame behind the lay and independent of it and having a rear opening and a front opening at its bottom and also a rearwardly-extending plate, a shuttle-box rotatably mounted on the lay and having an open top and an open bottom, means adapted to rotate said shuttle-box a quarter-revolution, a pusher supported by said rearwardly-extending plate and adapted to move a shuttle from the shuttle-reservoir into the shuttle-box when the shuttle-box is in its elevated position, a lever pivotally mounted on the loom-frame, a link-rod connecting the top of said lever with said pusher, a binder-shaft mounted on and movable with the lay, means adapted to rock said binder-shaft upon the failure of the filling-thread, and a lever-arm from the binder-shaft arranged to come into contact and to move the first-named lever, when said binder-shaft is rocked as aforesaid, substantially as described.

54. In a loom, the combination of a lay, a shuttle-receiving pan supported on the loom-frame behind the lay and independent of it and having an open front, a shuttle-box rotatably mounted on the lay and having an open top and an open bottom, means adapted to rotate said shuttle-box a quarter-revolution, a pusher in front of said shuttle-box and adapted to move a shuttle from the shuttle-box into the receiving-pan, a binder-shaft mounted on and movable with the lay, means adapted to rock the binder-shaft, a binder-finger fastened on the binder-shaft and extending upwardly, a vertical rock-shaft with suitable supports on the loom-frame, a bent lever fastened to the vertical rock-shaft at the bottom thereof and at a right angle thereto, one of whose ends is in line with the top

- of the binder-finger and movable thereby when the shuttle-box has been rotated to its elevated position and the other of whose ends has a spring-bearing against the loom-frame, 5 a bent lever-arm fastened at one end to the vertical rock-shaft at the upper end thereof and having its other end slotted, and a sliding rod mounted in suitable ways and connected to the pusher at its front end and at 10 its other end to the slotted end of the last-named lever-arm by means of a headed screw extending from the sliding rod through the slot of said lever-arm, substantially as shown.
55. In a loom, the combination of a lay, a 15 shuttle-receiving pan supported on the loom-frame behind the lay and independent of it and having an open front, a shuttle-box rotatably mounted on the lay and having an open top and an open bottom, means adapted 20 to rotate said shuttle-box a quarter-revolution, a pusher in front of said shuttle-box and adapted to move a shuttle from the shuttle-box into the shuttle-receiving pan, a vertical rock-shaft having an angular extension 25 therefrom and a spring, a lever-arm fastened to the top of said vertical rock-shaft and provided with a slotted end, and a sliding rod mounted in suitable ways and connected at its forward end with the pusher and at its rear end 30 to the slotted end of said first-named lever-arm by means of a screw passing therefrom through the slot of said lever, a binder-shaft properly mounted, means adapted to rock said binder-shaft, and an extension from the 35 binder-arm adapted to move the lower angular extension of the vertical rock-shaft when the shuttle-box is in its elevated position, substantially as specified.
56. In a loom, the combination of a lay, a 40 shuttle-receiving pan supported on the loom-frame behind the lay and independent of it and having an open front and an upwardly-extending arm, a shuttle-box rotatably mounted upon the lay and having an open top and 45 an open bottom, means adapted to rotate said shuttle-box a quarter-revolution, a pusher in front of said shuttle-box and adapted to move a shuttle from the shuttle-box into the receiving-pan, a binder-shaft mounted on and 50 movable with the lay, means adapted to rock the binder-shaft, a spring-pressed binder upon the shuttle-box, a binder-finger fastened at its bottom to the binder-shaft and having its upper end in contact with said binder, a lever pivotally mounted on the shuttle-box and having its shorter end located beneath said binder and its longer end extending in the line of the projecting arm of said shuttle-receiving pan when the shuttle-box is in its elevated position, a vertical rock-shaft with suitable supports on the loom-frame, a bent lever fastened to the vertical rock-shaft at the bottom thereof at a right angle thereto, one of whose ends is in line with the top of said 65 binder-finger when the shuttle-box is in its elevated position and the other of whose ends has a spring-bearing against the loom-frame,

a bent lever-arm fastened at one end to the top of the vertical rock-shaft and having a slot in its other end, a sliding rod suitably mounted in ways and connected with said pusher at its front end and to the last-named lever-arm at its other end by means of a screw extending therefrom through said slot, substantially as set forth. 75

57. In a loom, the combination of a lay, a shuttle-receiving pan supported on the loom-frame behind the lay and independent of it, and having an open front, a guide-plate upon the top of said pan, partially covering the 80 same, a rotatably-mounted shuttle-box upon the lay having an open top and an open bottom, means adapted to rotate said shuttle-box a quarter-revolution, mechanism arranged and operative to move a shuttle from the shuttle-box into the receiving-pan when the shuttle-box is in its elevated position, and springs or bars loosely mounted at their upper ends upon said guide-plate and capable of moving freely toward the interior of the receiving-pan but incapable of moving outwardly therefrom, substantially as shown and for the purpose specified. 85

58. In a loom, the combination of a lay, a breast-beam, a rotatable shaft having a cam 90 thereon, a bent lever mounted on the loom-frame having its lower end in operative contact with said cam, an oscillating weft-fork having a hooked end with which the upper end of said bent lever is engageable upon failure of the filling-thread, a sliding plate to which the weft-fork is pivoted and which is movable in proper guides, a rock-shaft mounted on said breast-beam, a lever-arm fastened on the rock-shaft and movable by the pressure upon its upper end caused by the sliding of the said plate, a holding-pawl pivoted on the loom-frame, a presser-arm fastened on said rock-shaft and bearing against the upper end of said holding-pawl, a ratchet-gear with 100 which said holding-pawl is engageable, a feeding-pawl having a counterpoise and pivotally mounted on said bent lever near the fulcrum thereof and having its lower end engageable with said ratchet-gear, a pinion on the same 105 shaft as the ratchet-gear and rotating therewith, a sand-roller having a gear meshing with said pinion, a cloth-roller receiving cloth from the sand-roller, and shuttle-transferring mechanism for removing a spent shuttle and supplying a fresh filled shuttle, the said parts being so arranged and timed in their movements that during the shuttle-transferring operation, the said holding-pawl is disengaged from said ratchet-gear thereby temporarily preventing the winding of the cloth upon the cloth-roller, substantially as specified. 110

59. In a loom having shuttle-changing mechanism whereby a spent shuttle is removed and a fresh filled shuttle is supplied, the combination therewith of a lay, a pair of shears, one of whose handles is pivoted to a fixed support on the lay, a rocking shaft and means adapted to rock it operative upon fail-

ure of the filling-thread, a collar-cam fixed on said shaft and having two diametrically-located deep notches and two diametrically-located shallow notches midway between the first-named notches, a ratchet-cam loosely mounted on said shaft and having two diametrically-arranged radial arms, four ratchet-teeth ninety degrees apart and two diametrically-arranged cam projections engageable 5 *seriatim* in said notches of the collar-cam, a bracket on the lay, a pawl pivotally mounted on the lay and having a downward extension, a ratchet-arm loosely mounted on said shaft beside the ratchet-cam, a spiral spring 10 rounding said shaft and having one end thereof bearing on the ratchet-arm and the other end bearing against a fixed collar on said shaft, a spring-pressed pawl mounted on the ratchet-arm and engageable with the teeth of 15 the ratchet-cam, a lever-arm mounted on said bracket, a spiral spring from this lever-arm extending to the downward extension of the first-named pawl, a link-bar pivotally connected with said last-named lever-arm at one 20 end and at the other with one of the handles of said shears, a spiral spring fastened to the last-named lever and extending to a fixed support on the loom-frame, a bracket adapted to support the ratchet-arm when the latter is 25 not in operation, and a bunter extending from the breast-beam, all arranged and operating substantially as and for the purpose specified.

60. In a loom having shuttle-changing mechanism whereby a spent shuttle is re-

moved and a fresh filled shuttle is supplied, 35 the combination therewith of a lay, a pair of shears pivotally mounted on the lay, a shuttle-reservoir with shuttles therein, a thread-lever pivoted on a fixed support and having a weighted lower end and an upper end adapted 40 to receive and hold the ends of the weft-threads of said shuttles, a shuttle-box adapted to receive a shuttle from said reservoir, a filling-detector, and means intermediate between the filling-detector and shears, operative 45 upon failure of the filling-thread and adapted to close said shears so as to cut the weft-thread between the blades thereof which extends from the newly-supplied weaving-shuttle to said thread-lever, substantially as 50 described.

61. In a loom, the combination of a lay, a movable shuttle-box on the lay, a shutter or guide pivotally mounted in suitable bearings at the top near the open end of said shuttle-box above the path of motion of the shuttle and normally extending in a plane therewith, means operative upon failure of the filling to move said shuttle-box and partially rotate the shutter toward the interior of the shuttle-box during the backward movement of the lay and return the same to their normal position during the forward movement of the lay, substantially as described.
